United States Patent Office.

DOUGLAS W. EATON, OF NORTH RIDGE, NEW YORK.

Letters Patent No. 93,976, dated August 24, 1869.

IMPROVEMENT IN DEVICE FOR TIGHTENING WIRE FENCE.

The Schedule referred to in these Letters Patent and making part of the same.

To all whom it may concern:

Be it known that I, DOUGLAS W. EATON, of North Ridge, in the county of Niagara, and State of New York, have invented a certain new and useful Improvement in Devices for Straining Wire Fence; and I do hereby declare that the following is a full and exact description thereof, reference being had to the accompanying drawings, making a part of this specification, in which—

Figure 1 is an elevation of the fence, with my improvement applied thereto.

Figure 2, a plan of the same.

Figure 3, a view of the straining-instrument, detached.

Like letters of reference indicate corresponding parts in all the figures.

My invention consists of an instrument of peculiar construction, for straining wire fence, being in the form of a wrench, with cross-arm at one end, and a smooth conical point at the other, by which means it can be tightened or loosened at pleasure.

In the drawings, a section of wire fence is shown, being of that kind where pickets are woven with a double strand of wires at top and bottom. In this construction the strands have to be alternately crossed to receive the pickets, to accomplish which requires that the wires should be frequently slackened and drawn taut, to admit and hold the pickets. This requires a tightening-device which is capable of nice adjustment, and also capable of tightening and slackening with great facility.

My tightening-device consists of a straight shank, *a*, having a head, *b*, at one end, through which passes a cross-arm, *c*, as is usual in wrenches and vises, and smooth, tapering point, *d*, at the other, which enters a corresponding hole in the fence-post.

The extremity of the conical end may be cleft or notched, as shown at *f*, so that when driven into the wood, it will clinch and hold with greater tenacity.

The shank is provided with one or more holes, *g*, for receiving and securing the ends of the wires to be strained.

The action will be readily understood.

The wire being secured to the wrench, the conical end of the latter is placed in the corresponding hole in the post, and turned, by means of the cross-arm, to

the necessary degree to make the wire taut. The pressure of the operator's hand inward will be sufficient to secure it for the time being, or if this is not enough, it may receive the blow of a hammer. In releasing, for the insertion of the picket, the smooth surface of the conical point offers no substantial impediment to the turning-action, and thus great accuracy of adjustment may be secured, and the necessary tension and slack produced in the simplest manner.

I am aware that screw-bolts, screwing into the wood, have been before employed for straining and holding the tension of wire fences; but in such cases they have been of small size, and attached to the posts as fixtures.

My invention differs from these, in being made of large size, as a wrench, and not being a fixture to the post, but simply a device for straining the wire, which is then fastened, while the instrument itself is removed.

It is obvious at a glance that a screw-bolt could never answer the purpose for which my instrument is designed.

I am also aware that wrenches of various forms are in use. I disclaim the use of a wrench, broadly.

My instrument is of special construction, as the point *d* must be made conical to hold in the wood as it is forced in, and must be made round and smooth to allow a turning-action without removal from the wood.

These features of the wrench are what render the device practical for this particular purpose, and have never before been embodied in a wrench, so far as I am aware.

What I claim as my invention, and desire to secure by Letters Patent, as a new article of manufacture, is—

The device for straining wire fences, herein described, consisting of the shank *a*, with conical point *d* and cross-arm *c*, the whole arranged as described, and operating in the manner and for the purpose specified.

In witness whereof, I have hereunto signed my name, in the presence of two subscribing witnesses.

D. W. EATON.
